(57) **CLAIM**

The ornamental design for hummingbird feeder partition, as shown and described.

DESCRIPTION

FIG. 1 is a perspective view of a hummingbird feeder partition showing my new design;

FIG. 2 is a front elevational view of the invention;

FIG. 3 is a rear elevational view of the invention;

FIG. 4 is a right-side elevational view of the invention;

FIG. 5 is a left-side elevational view of the invention;

FIG. 6 is a top plan view of the invention;

FIG. 7 is a bottom plan view of the invention; and,

FIG. 8 is an enlarged perspective view of a single partition. Broken lines and unshaded portions contained within broken lines are not claimed.

1 Claim, 5 Drawing Sheets(56)
